UNITED STATES PATENT OFFICE.

WILLIAM MORGAN PETERS, OF CHICAGO, ILLINOIS, ASSIGNOR TO THE
ADAMS & WESTLAKE COMPANY, OF SAME PLACE.

DESIGN FOR A PANEL FOR THE FOOT OR HEAD OF BEDSTEADS.

SPECIFICATION forming part of Design No. 29,284, dated August 30, 1898.

Application filed August 1, 1898. Serial No. 687,448. Term of patent 7 years.

To all whom it may concern:

Be it known that I, WILLIAM MORGAN PETERS, a citizen of the United States, and a resident of Chicago, county of Cook, and State of Illinois, have invented and produced a new and original Design for a Panel for the Head or Foot of a Bedstead, of which the following is a specification, reference being had to the accompanying drawing, forming a part thereof, and which shows the design in elevation, the essential portions of the design being shown in solid lines and the non-essential portions being shown in dotted lines.

The design is composed of a plurality of round rods wrought into the following-described forms:

As shown in the drawing, the leading or central feature of the design is a pair of scrolls A, the main portions of which are approximately in arc form and have approximately a vertical direction. The two arcs bear away from each other, and their upper ends are prolonged to the sides of the design and turned downwardly, forming the spirals a. The lower ends of the scrolls A A are wrought into the form of geometrical spirals, as shown at a', and extend laterally to a less distance than the upper spirals a a. Above and below the point of nearest approach to each other of the body portions of the scrolls A A and in contact with each of these scrolls are located a pair of circles B B, the lowest points of the lower circle being in horizontal alinement with the lowest point of the spiral a' a'. Included within each of the spirals A there is a geometrical spiral C, having its outer end recurved inwardly, as shown at c, this

recurved end and also the second turn of the spiral C contacting with the spiral a'. Across the upper portion of the design are a pair of scrolls D D, taking substantially the form of the letter S, but having a generally horizontal direction. Both ends of each of these scrolls are continued in spiral form. The two inner spirals of the scrolls D D touch each other and also the upper circle B and the body portion of the scroll A A. The outer portions of the scrolls D D touch the scroll C, and each is contiguous to one of the spirals a.

At the point of the nearest mutual approach of the scrolls A A and C C these several scrolls are tied together by an annularly-ribbed spindle M, and a similar spindle m unites the outer and second convolutions of the spiral C C.

The design is inclosed within a border consisting of the upper and lower rails E F and the vertical rods G H, and within each of the lower corners of the design there is located a vertical rod K, rising from the rail F, and contacting with the outer convolution of the spiral a', and being curved outwardly at its upper end to the vertical border-rods, touching by its curved portion the spiral C.

The border and the rods K K do not form an essential part of the design. 65

I claim as my invention—

The design for the head or foot of a bedstead, substantially as herein shown and described.

WM. MORGAN PETERS.
